UNITED STATES PATENT OFFICE.

WILLIAM S. RUSSELL, OF TOLEDO, OHIO.

EXCAVATOR.

SPECIFICATION forming part of Letters Patent No. 617,605, dated January 10, 1899.

Application filed July 25, 1898. Serial No. 686,822. (No model.)

To all whom it may concern:

Be it known that I, WILLIAM S. RUSSELL, of Toledo, in the county of Lucas and State of Ohio, have invented certain new and useful 5 Improvements in Excavators, of which the following is a full, clear, and exact description, reference being had to the accompanying drawings and to the letters of reference marked thereon.

10 My invention relates especially to machines used for excavating earth and other material by means of a dipper so constructed as to take up the load, elevate it, swing it toward either side of the machine, dump it, and be returned to position to take another load. 15 These machines are usually mounted on wheels for land use and are commonly called "excavators," "steam-shovels," or "land-dredges."

20 The purpose of my invention is to equip an excavator, steam-shovel, or land-dredge with an efficient device, amply strong and simple, for supporting the front end of machine and also for turning the whole main car and frame 25 completely around end to end to reverse it in order that it may work in either direction.

The purpose and use of the turn-table hereinafter described is, first, to support the front end of machine while working or moving over

30 the rails, and, second, to support the whole machine entirely on a point of balance while being swung or turned around. In order to accomplish this, the turn-table is detachable from and not fastened to car-body, being 35 loose, but held in place by metal rings having flanges and which form a seat to receive the upper ball-bearing ring of turn-table. There are two of these metal flange-rings, which are securely fastened to under side of car-body, 40 one of these being directly under front end of car and the other back toward middle of car at point of balance.

In order to turn the machine around, the front end of car is raised by means of jack-screws until the flanges on metal ring are clear of turn-table. The turn-table is then slid or moved back under the balance-ring, and machine is lowered down in place, the whole weight resting upon turn-table.

45 50 I have shown my invention as applied or in connection with an ordinary excavator or

steam-shovel of the crane type; but it may be used on excavators of other styles which are provided with a boom and dipper or other means of raising, swinging, and dumping the 55 load, while the car or main body of machine remains stationary.

In the drawings, Figure 1 is a side elevation of a crane-excavator, illustrating the application of my improvements, showing the excavator supported at front end by turn-table truck in full lines and at rear end by a plain center-pin truck in working position and the position of turn-table when moved back to second or middle ring at center of balance 60 being indicated by dotted lines; Fig. 2, a longitudinal section of turn-table and metal flange-rings on a larger scale; Fig. 3, a transverse section, on about line 3 3, Fig. 2, of turn-table, showing metal flange-ring as fastened 65 to car-body, also the girder jack-arms extending across car and fitted with heavy screws used in raising front end of car and also to steady it while working. Fig. 3 also shows turn-table wheels and axles and center plates. 70 Fig. 4 is a top plan of turn-table with view of roller-bearing in part cut away. Fig. 5 illustrates in detail sectional perspective the metal flange-ring, ball-bearing races, and base or 75 I beam.

In Fig. 1, A represents the main car-body of excavator; B, the crane; C, the dipper; D, the dipper-handle; E, the swing-circle, used for swinging the crane around in order to dump the load; F, the mast or crane-post; G, 80 the main hoisting-drum; H, the hoisting-engine; I, the swinging-engine; J, the crane-thrusting engine; K, the boiler, and L the rear truck.

In Fig. 2, M M' represent the metal flange-rings, which are fastened to under side of car; N N', the upper and lower ball-races, with turned grooves N² in their adjacent faces; O, the steel balls, which afford the means for supporting a very heavy weight while turning 95 with the least friction.

P is the main or base turn-table ring, made of steel I-beams strongly braced with cross-beams P' and girths P².

Q is the square part of truck-frame, made 100 of suitable I-beams and channel-beams fastened with angles and strongly braced, which

is supported by the car-wheels, four in number, and axles fitted with double bearings, as shown.

The beam M is provided in its under side with the annular groove m , which receives the upper ball-race N and holds the same steadily in its place. The lower ball-race N' has a grooved connection with the base-beam P, being preferably provided with a groove n^2 , fitting on the said beam P, as shown. The seat M' is similar to the seat M and is adapted to receive the upper ball-race N when the turn-table is adjusted rearward, as indicated in dotted lines, Fig. 1. The object and use for which this turn-table is designed is to afford a means of turning any style of excavating-machine to which it may be fitted completely around or end for end, so that upon finishing a cut the apparatus may be turned around and begin another cut in an opposite direction or at right angles, if so desired. This turn-table is capable of sustaining the entire weight of the excavator upon the rails on which it is worked when it is to be turned around and also to support the front end of machine when working.

The jack-arm girder R extends at both ends laterally beyond the car body or platform and supports at its ends the threaded bearings S' for the upright jack-screws S, which may be utilized to raise the end of the car and also to serve as lateral braces to stay the car-platform in a lateral direction. This jack-arm is of a special construction, being formed with the upper beam R' and the lower beam R ^{2} , extended, respectively, above and below the car body or platform and bolted firmly in position. The extending ends of the beams R' R ^{2} support the threaded bearings S' between them and are suitably braced, preferably by the lattice-bars R ^{3} , as shown.

The turn-table truck has at its center the center bearing T, in which rests the pivot-piece T' on the car-platform, such pivot-pieces being arranged centrally of both rings or seats M and M', as shown.

In the practical operation of my excavator, owing to the slight friction of ball-bearing turn-table, the car may be easily turned by four or five men pushing against the rear side and without the aid of any mechanical device. The raising of the rear end of car, so that the wheels on rear truck may clear the rails, is accomplished by running the long dipper-handle with dipper attached out to its extreme length, which will extend forty feet from the mast at the front end of car, also by running the water down in tank under boiler, which when full contains ten hundred and sixty gallons. This will lighten rear end, so it will be overbalanced by the other end. In ordinary working the car is operated upon short sections of rails eight feet long, which rest loose upon the ties. It is not necessary to raise the rear truck-wheels so high that the flanges clear the rails, but simply to raise them one-fourth of an inch. The short rails

are then pulled out from under the wheels, leaving all clear, and in case there is no steam in the boiler to thrust the dipper out a jack-screw may be used under the rear end to raise it to the required height.

It will be understood that when the dipper is pulled in on the crane and the tank is full of water the car is then in balance on turn-table, placed under middle ring.

Having thus described my invention, what I claim as new, and desire to secure by Letters Patent, is—

1. In an apparatus substantially as described the car body or platform having a truck at one end and having at or near its other end a seat for the turn-table truck and having a similar seat between such end seat and truck, and the turn-table truck having wheels to run on the rails and fitted at its upper end to the intermediate and end seats of the car body or platform whereby it may be shifted to serve its dual functions substantially as set forth.

2. In an apparatus substantially as described, the car body or platform combined with the turn-table truck shiftable from a point at or near one end of the car to a point at or near the middle thereof substantially as set forth.

3. An apparatus substantially as described comprising the car body or platform having at or near its end and at or near its middle, the seat-beams provided in their under sides with grooves and the turn-table truck having the top ring fitted to such grooves substantially as set forth.

4. An apparatus substantially as described comprising the car body or platform, the permanent truck at one end thereof, the seats for the shiftable truck at or near the opposite end of and at or near the center of the platform and the shiftable truck fitted to said seats and adapted to be shifted from one to the other thereof substantially as shown and described.

5. An apparatus substantially as described comprising the car body or platform, the seat-beams having the grooves in their undersides, the truck-frame having the circular beam at its upper side, the upper ball-race ring fitted in the groove of the seat-beam, the balls and the lower ball-race ring having a grooved connection with the circular beam at the top of the truck-frame substantially as set forth.

6. An apparatus substantially as described comprising the car body or platform, the turn-table truck shiftable between positions at or near the end and at or near the middle of the car-body and the jack-arm secured to the car body or platform and extended at its ends beyond the same, and provided with the screws substantially as set forth.

7. An apparatus substantially as described comprising the car body or platform, the excavating devices thereon, the ring-seats beneath and at or near the middle and one end of the platform, the permanent truck at one

end of the platform, the turn-table truck fitted to said ring-seats and adapted for adjustment to support one end of the platform or support the same at its center of balance and the jack-arm secured to the car-platform having its ends extended beyond the same and provided with the screws substantially as set forth.

8. The improved apparatus herein described consisting of the car body or platform, the excavating devices thereon, the jack-arm composed of beams extended above and below the car-body, the lattice brace-bars

between said beams, the screws connected with the jack-arm, the ring-seat near one end of the car-body, the ring-frame near the middle of the car-body, the permanent truck at one end of the car and the turn-table truck having a lower ball-race, and an upper ball-race, the latter being fitted to the ring-seat of the car-body substantially as set forth.
